UNITED STATES PATENT OFFICE.

ALFRED C. NORTH, OF ELKHART, INDIANA.

SALES-BOOK MAKING AND PRINTING MACHINE.

1,010,677.

Specification of Letters Patent.

Patented Dec. 5, 1911.

Application filed April 2, 1909. Serial No. 487,483.

To all whom it may concern:

Be it known that I, ALFRED C. NORTH, a citizen of the United States, residing at Elkhart, in the county of Elkhart and State of Indiana, have invented certain new and useful Improvements in Sales-Book Making and Printing Machines, of which the following is a specification.

This invention relates to improvements in printing machines and more particularly to an improvement in a machine for printing sales books, the object of the invention being to provide a device of this character in which one or more printing presses work in conjunction with numbering machines, perforating machinery and a cutting mechanism and feeding and roll unwinding mechanisms whereby paper from one or more rolls of the same or different paper and of the same or different colors may be printed.

Further objects and advantages of the invention will be set forth in the detailed description which now follows:

In the accompanying drawings, Figure 1 is a vertical section of the entire machine with the exception of the folding device. Fig. 2 is a plan view of the machine, Fig. 3 is a rear end elevation of a portion of said machine illustrating an adjustable take-up, 30 guide, and helper, and pull-back rollers. Fig. 4 is a plan view of means for accelerating or retarding the unwinding of the paper. Fig. 5 is a side view of the perforator, Fig. 6 is a plan view of the perforator.

35 A folding device may be added to the machine after the knife, but this folding device forms no part of the present invention and it is accordingly not claimed.

Like numerals designate corresponding parts in all of the figures of the drawings.

Referring to the drawing, it will be seen that the bed of the machine comprises an elevated portion 5 and a depressed portion 6, said frame being supported upon legs 7 which are braced and tied together by suitable cross bars 8. Motion is imparted to the entire structure by belt 9 which passes around pulley 10, said pulley being fixed to shaft 11 which is the main shaft of the 45 entire mechanism. The gear wheels herein-after described are ordinary spur gear wheels and their positions have merely been indicated to aid in preserving the clearness of the drawing. Indicated gear wheel 12 is 55 fixedly mounted upon shaft 11 and engages indicated gear 13, Fig. 1, which operates the

mechanism mounted upon the elevated portion 5 of the frame. The indicated gear 14 which also meshes with gear 12 operates the mechanism mounted upon the depressed portion 6 of the machine, the last named gear being journaled to frame 15 by a pin 16. 60 17 designates a second threaded opening for pin 16 whereby the gear 14 may be mounted in another adjustment. 18 designates a 65 third threaded opening for a similar pin 18' carrying an indicated extra gear 19 for reversing the movement of the entire mechanism mounted upon the depressed portion 6 of the machine frame. This extra gear 19 70 is removed when gear 14 is mounted in the uppermost position indicated in Fig. 1.

When the mechanisms upon the depressed part of the frame are rotating in one direction the drive is from the gear 12 directly 75 through gear 14 to gear 22, gear 14 at this time being mounted upon the pin 16, but when these mechanisms are to run in the opposite direction, the idle gear 19 is interposed by mounting it upon the pin 18', this 80 idle gear at that time meshing with the gear 12 and with the gear 14, it being understood that at this time the gear 14 is lowered by inserting its pivotal mounting in the opening 17, though the gear 14 still remains in mesh 85 with the gear 22.

The reason for sometimes reversing the movement of the mechanism mounted upon the depressed portion of the machine frame, as well as the reason for having the web 90 alternately tight and loose and having it sometimes retarded and sometimes accelerated, will be clearer if it is remembered that there are two great classes of salesbooks at present in use, both of which may be made 95 by this machine. These classes are grocers' books and drygoods books, the drygoods books being made from a single web, while the grocers' books comprise two webs. In drygoods books the margins are very wide, 100 while in grocers' books, the margins are very narrow. When printing drygoods books, the segments hereinafter described are rotated in such direction with relation to the web that they become helpers to help the 105 web along to take care of the wide margins of this class of books. When grocers' books are being made, the segments rotate in the opposite direction and become retarders to hold back the web on account of the narrow 110 margins of this class of books.

20 designates an anti-friction roller, the

purpose of which will be hereinafter described.

The printing press indicated in a general way at 21 and located upon the depressed portion 6 of the frame of the machine is exactly like corresponding printing presses on the upper portion 5 of the frame of the machine, and an explanation of one of these machines will serve as an explanation of both. The printing presses together with the numbering machines serve as auxiliary feeds for the web.

Idle gear 14 engages the indicated gear 22 which is keyed to shaft 23, said shaft operating the printing press 21. An indicated idle gear 24 which meshes with and is driven from gear 22 is keyed to a shaft 25 and engages indicated gear 26 which operates a numbering machine designated in a general way at 27. The gears 22, 24, 26 each have forty-nine teeth so that they will rotate in unison and so that an indicated sprocket wheel 28 mounted upon shaft 25, will also rotate in unison with the printing press and the numbering machine.

Means for accelerating or retarding the unwinding of the paper webs upon which the sales books, invoices, and the like are printed, are shown at the right hand portion 30 of Fig. 1 and in Fig. 4. By referring to these figures, it will be seen that bearing standards 29, the legs of which are tied together by cross bars 30, support spindles 31 upon which the paper rolls 32 and 33 are mounted. Upwardly inclined arms 34 of the bearing standard support swinging arms 35, said swinging arms being pivotally connected to the upwardly extending arms by shafts 36 and 37. At the outer ends of the swinging arms are located shafts 38 and 39. Cone pulleys 40 and 41 are mounted upon the shafts 36 and 37 and cone pulleys 42 and 43 are mounted upon the shafts 38 and 39. Indicated belts 44 and 45 are adapted to be shifted laterally by means of a belt shifter 46 into which a transverse screw 47 is threaded. A rod 48 passes through this belt shifter and serves to guide it. A hand wheel 49 serves to impart rotation to the screw 47 to move the belt shifter transversely between the arms 35 and since the cone pulleys 38 and 39 are driven by means of the belts 44 and 45 from the cone pulleys 40 and 41, it is apparent that the rate at which the paper rolls are unwound may thereby be varied, this unwinding being accomplished by friction rolls 50 and 51 having rubber bands 52 mounted upon their peripheries in contact with the peripheries 60 of the paper rolls. Counter weights 53 adjustable by means of set screws 54 are mounted upon rearward extensions 55 of arms 35 and control the frictional contact of the frictional rolls with the paper rolls. Sprocket wheels 56 are mounted upon the

shafts 36 and 37 and indicated sprocket chains 57 and 58 drive these sprocket wheels, motion being imparted to said sprocket chains from a portion of the machine hereinafter described.

A indicates the paper web from roll 32, this web passing under the machine and around a transverse bar 59 which is carried by a rearwardly projecting portion 60 of the machine frame. The web then passes between adjustable guide faces 60' (see Figs. 1 and 3) over a roller 61 and under a brake 62, through pull-back devices 63, under brake 64, through the numbering machine, then under a brake 65, then through a printing press, then under a brake 66, and then on to a perforating mechanism hereinafter described. B designates another slack paper web delivered from roll 33 and passing under the machine around bar 67, over roller 68 and under pull-back 69, then under brake 70, through the numbering machine under bar 71, over bar 72 and through the printing press 21, then under bar 73, and over shaft 11, under the transverse bar 74, up to and over a transverse bar 75 and beneath the brake 66, after which it follows the path of the web A. C is a third web usually of tissue paper and drawn from a roll 76 journaled in brackets 77. This web enters the machine under brake 66 and it will be noticed that it enters between the webs A and B. The brake or tension fingers 62, 64, 65, 66, 70, etc., prevent over-running of the slack portions of the webs when these slack portions are increased, owing to the acceleration of the webs by the action of the helper segments such as 94, or the action upon the web of the printing or numbering machines. In addition to this, the guide collars 202 hereinafter described, during this acceleration of the web, prevent side movement of the web and preserve its transverse alignment.

The structure shown in Fig 3 is an adjustable upright take-up frame, consisting of side bars 78 which are pivotally mounted upon the transverse rod 67, the inclination of the structure as a whole being controlled by screw rods 79 which are threaded in nuts 80 of the frame of the numbering machine and which turn loosely in swivel blocks 81 carried by the side bars 78, said screw rods carrying fixed collars 82 located upon each side of said swivel block. Hand pin 83 provides means for turning the screw rods to thereby vary the inclination of the adjustable upright take-up frame as a whole. Varying the inclination of the take-up frame, renders it possible to more completely control that portion of the web leading from the top of the take-up frame to the mechanisms which act upon said web. It will be seen that this is an important feature when it is considered that sheets of varying

lengths are at various times acted upon by of the machine. These collars maintain the said printing mechanisms. side registry of the paper while the tension

An indicated sprocket chain 84 passes over sprocket wheel 28 and over a sprocket wheel 85 which is fast upon the shaft of roller 68. A second sprocket wheel 86 is also secured to this shaft and rotates therewith. A link belt 87 is engaged by this last named sprocket wheel and has motion imparted thereto from said sprocket wheel. This link belt passes over an idler sprocket 88 and over an indicated sprocket wheel 88' which is fast upon a shaft 89. This shaft carries a helper or retarder segment 90, said retarder segment being adjustable upon said shaft by means of a set screw 92. This segment is provided with a leather or other soft face 91. At its upper end, the link belt passes over an indicated sprocket wheel 92 which is mounted upon a shaft 93, said shaft carrying a helper or retarder segment 94 which is also provided with a leather or other soft face 95. The link belt also passes over an indicated sprocket wheel 96 mounted upon a shaft 97, it being understood that the helper or retarder segments are bodily rotated and that their soft faces impinge upon the peripheries of the rollers 68 and 98, or rather upon the webs which pass between these members.

12 The gear 201 having forty-nine teeth and loose on shaft 202', journaled in bearings of side frames 203, operates a perforating mechanism, (see Figs. 5 and 6). The gear 201 is adjustably fastened to the shaft 202' by a slotted segment 204. A gear 205 is keyed to the other end of shaft 202' and actuates a gear 206 loose on shaft 207. Gear 207 is adjustably fastened to said shaft by a slotted segment 208. Fixed to shaft 202' is an iron impression cylinder 209 covered with a hard paper or soft metal tympan in the usual way. Another iron cylinder 210 is fixed to shaft 207 and on said cylinder is adjustably screwed or otherwise fastened one or more perforator holders 211 screwed to cylinder in any place desired by a choice of any of a number of threaded openings 212. These holders carry a strip of steel perforating rule 214 secured in place by screws 213. One or more of these perforating bars may be mounted on cylinder 210 at the proper places to secure registry, which, when secured, is usually the same for all classes of work of two lines of perforations or more. For one line of perforation per revolution, any position will do, as the general registry is obtained by in-

15 20 25 30 35 40 45 50 55 60 65 70 75 80 85 90 95 99

The guides 60' are laterally adjustable upon fixed wooden rollers 99 and 100. To accomplish this end, set screws 101 are provided, said set screws passing through the guides and entering said wooden rollers.

102 and 103 are anti-friction rollers that extend laterally between the side bars of the upright take-up frame.

A brake finger 104 is pivotally mounted upon a shaft 105 and its free end bears upon the web at the point where said web passes over the anti-friction roller 61.

The arms 197 of a take-up bar 198 are fastened to the side frames by a threaded rod 199, this bar being used occasionally in securing registry between the press and the perforator. An indicated gear wheel 200 communicates motion from the last press to indicated gear 201 operating a perforator. Full details of these parts are accurately shown in Figs. 5 and 6, and it is to be understood that in Fig. 1, certain of the parts are omitted, said figure serving merely to indicate the location of the various mechanisms with relation to each other. Adjustable paper guide collars 202 (see Fig. 2) 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000 1005 1010 1015 1020 1025 1030 1035 1040 1045 1050 1055 1060 1065 1070 1075 1080 1085 1090 1095 1100

are placed on suitable cross rods throughout the machine and are used in conjunction with brake or tension fingers such as are shown at 66, the general principle being, that wherever a periodic slack occurs in the paper, guide collars are needed immediately before or after and a tension finger immediately after said slack portion, otherwise the paper would not continue seeking the center

into threaded nut 234 to thereby raise and lower the paper web and act as a take-up between the perforator and the knife.

Inside of gear 228 and loosely fitting around the outside of the box in which shaft 226 is journaled, fits one end of a bell crank lever 235, the outer end of which carries a fixed stud 236 on which a loose gear 237 is mounted, said gear meshing with and being moved by the gear 228. Also loose on stud 236 and fixed to gear 237 by a stud pin 238, is another gear 239, both of said gears being held on the stud by a nut 240. At the lower end of lever 235 is a slotted opening 241 in which fits a cap screw 242, said cap screw screwing into frame 227. This structure permits adjustments of lever 235. The gear 239 meshes with and drives a gear 243 which is fastened to shaft 244 by set screw 245 or otherwise. Gears 228 and 237 may be of any size and interchangeable. Also gears 239 and 243 may be of any size and interchangeable, and since sets of gears of different sizes may be employed, it is apparent that shaft 244 may be made to revolve at many different speeds, a slow speed causing a short sheet of paper to be cut off and the greater the speed, the longer the sheet.

The middle portion of shaft 244 is enlarged at 244*, see Fig. 5, the paper web passing over said enlarged portion which is in the form of a roller, said roller serving to pull the paper on its under surface. The shaft 244 is journaled in side frames 227 and 35 at its opposite end carries a fixed gear 246 engaging a gear 247 which is fixed to a shaft 248. This shaft is journaled in throw-off arms 249 having fixed to their outer ends a slightly grooved cross plate 250 which is 40 raised in Figs. 5 and 6 and lowered, and engages the paper in Figs. 1 and 2.

Adjustably fixed by set-screws or otherwise, to shaft 248 is a set of feed wheels 251 usually run on margins of the uncut sheets 45 to prevent smutting, as shown in Fig. 2, although shaft 248 may be enlarged and used as a feed roller by running the ink lighter. Fastened to frames 227 is a cross plate 252 with a raised center rib 253, the use of which 50 is explained later. Besides operating the feed mechanism, gear 225 operates intermediate gear 254 pinned to side frame 227. Said gear in turn moves gear 255, keyed to shaft 256, journaled in bearings in side 55 frames 227 and carrying at its opposite end another similar gear 257, both engaging two similar forty-nine tooth gears 258 keyed to short shafts 259, journaled in vertical supports 260. These shafts have keyed to their 60 inner ends, arms 261 having keyed in their outer ends, knife holder pins 262 to which is bolted or otherwise fastened a V cutting knife 263. This knife has a shear cut beginning at each outer end and severing the paper at the center. Since, while being cut,

the paper is temporarily obstructed by the knife, as the feed is in continuous motion pushing the paper forward, it is obvious that such obstruction should be of as short duration as possible. By cutting from outside to center, the angle or shear may be double that of cutting clear across and the paper obstructed no longer. Thus, by this means I secure a self-sharpening clean cut knife and double the cutting angle. Fastened to frame 227 is the lower straight flexible blade 264. The outer cutting corners of knife 263 are slightly dressed off at 265 to prevent riding on said knife. Since long sheets are obstructed proportionally greater than short ones, grooved cross plate 250 when down is sufficiently above cross plate 252 and rib 253 for the paper to move freely while rib 253 slightly kinks or bends the paper upward. Thus, while the knife is obstructing the paper and the feed is forcing it forward it simply kinks or bends farther upward into the hollow of plate 250 only to spring forward and regain its normal position again when said knife passes by. Bolted to lower forward end of side frame 227 is an arm 266 pivoted to outer end of which is an oscillating upright bar 267, carrying loosely on its upper end a connecting rod 268 with its outer end forming a box 269 about knife holder pins 262. Inward projections 270 and 271, a part of boxes 269, have bolted to their under sides a cross bar 272 with depressor fingers 273 fastened to their under sides. While gears 258 through 10 arms 261 revolve knife 263 as a single piece, fingers 272 have a circular motion up and down, following the knife and restrained from turning around by the arm 268, the knife holder pins 262 turning in the box 269. Thus fingers 273 become a fly to depress the severed sheets which fall upon a table 274 fastened to frames 227 and provided at its outer end with a fastened back-stop 275. To set the knife to cut the web at the proper place, intermediate gear 252 may be detached by removing the pin, after which, the knife may be turned to any point and again gear 252 being fixed, the paper is cut in another place without the general register being changed. For slight changes in cutting, drum 231 may be raised or lowered by screw rods 232, while the machine is in motion and the same is true of other take-up bars through the machine.

The various braking or tension fingers restrain the paper from continuing its forward movement by inertia or the pull of static electricity after the printing plates release the paper. In most rotary presses, the 125 plates are continued around the cylinders but in this machine they occupy only a small segment of the face of the cylinder and while these plates are actually engaged with the paper web, they shove the web forward 130

much faster than the feed rollers take it up and it is the function of the tension fingers to stop the forward movement of the web as soon as it is released by the printing plates. 5 Since the feed rollers 251 are only three narrow rollers running on the margins between the printed parts, they will not pull the paper through the machine without tearing it. If for instance, the sheets or leaves of a 10 book are to be six inches long and the feed rollers feed the web that distance during a complete revolution, it is apparent that the press printing with a six inch plate, which only takes up one-fourth of the surface of a 15 cylinder, will push the paper forward as much in one-fourth of a revolution as the feed rollers can take up in a whole revolution. The web therefore, for three-fourths of a revolution is loose in front of the press. 20 As the presses, numbering machines, and helpers act at different times, they help the paper forward and relieve the feed but they act at a much greater speed for a portion of their revolution than the normal speed feed 25 of the feed rollers. Thus during an entire revolution the paper is here and there seized and pushed quickly forward but held from going too far by the tension fingers. The same thing is true of the perforating and 30 numbering mechanisms. That is, these mechanisms act as auxiliary feeds in the manner above set forth.

As to the mode of operation, it may be first said that the machine may be run with- 35 out number attachments, or without perforators, or even without presses as is common in making blank pads. The demand for the various products widely exists wherever there are merchants or business men. 40 While I am aware that other machines mostly with reciprocating parts, irregular movements, and bed and platen presses have been constructed for similar purposes, and also rapid machines making only a single 45 size book have been made, yet, this machine is rotary throughout, simple, and very rapid. This machine is easily adjusted to make any length and width of leaf and actually can make nearly all of the non-duplicating, du- 50 plicating and triplicating blanks so common and useful in the mercantile trades. The only time that this machine could run with a tight web from the roll is when the length of sheet is practically the same as the dis- 55 tance around the printing cylinders. It is then a one size sheet machine and in that case, when using a tight web, no paper un-winding device is needed. But since it is frequently desired to vary the size of the 60 sheets, it will be seen that the various take-up and hold-back devices for the slack web are of the utmost importance.

The machine is shown threaded in Fig. 1 with three webs traced to the point 66 to 65 where they come together and travel as one

web between perforating cylinders and to the knife mechanism. This illustrates readily to one versed in the art, the mode of opera- 70 tion in one class of triplicate work. If du- plicate work is desired, then paper roll 76 75 is not used. If it is desired to print and number on both sides of a single web, com- mon to what are called dry goods books, then web A or B may be used, but it enters the machine over rod 74 (when tension finger 75 276 is used) under rod 72, over rod 71, under rod 70, around 103 and 102, after which, it follows the course of web A before shown; but in this case, the lower portion of the ma- 80 chine is reversed as before explained by the use of idle gear 19.

Since anyone skilled in the art can easily see the various ways of threading and means of manipulating by the explanation above given to secure the various results desired, 85 entering into the subject further would seem unnecessary.

From the foregoing description, it will be seen that simple and efficient means are herein provided for accomplishing the ob- 90 jects of the invention, but while the ele- ments shown and described are well adapted to serve the purposes for which they are in- tended, it is to be understood that the inven- 95 tion is not limited to the precise construction set forth, but includes within its purview such changes as may be made within the scope of the appended claims.

Having described my invention, what I claim is:

1. In a salesbook printing machine, the combination with a pair of printing ma- 100 chines, of means for driving one of said machines either in the same direction or in the opposite direction to the other of said machines, means for feeding an alternately tight and loose web through said machines, a rotative segment means for driving said segment from one of said printing machines, said segment acting when said last named printing machine is driven in one direction, 110 to accelerate said web, and acting when said printing machine is driven in the opposite direction, to retard said web.

2. In a salesbook printing machine, the combination with a pair of printing ma- 115 chines, of means for driving one of said ma- chines either in the same direction or in the opposite direction to the other of said machines, means for feeding an alternately 120 tight and loose web through said machines, a rotative segment means for driving said segment from one of said printing machines, said segment acting when said last named printing machine is driven in one direction, 125 to accelerate said web, and acting when said printing machine is driven in the opposite direction, to retard said web, a manually operable swinging frame in which said seg- 130 ment is mounted, and a feed roller in said

frame over which the web is threaded and with which said segment co-acts.

3. In a salesbook printing machine, the combination with a pair of printing machines, of means for driving one of said machines either in the same direction or in the opposite direction to the other of said machines, means for feeding an alternately tight and loose web through said machines, 10 a rotative segment means for driving said segment from one of said printing machines, said segment acting when said last named printing machine is driven in one direction, to accelerate said web, and acting when said 15 printing machine is driven in the opposite direction, to retard said web, a plurality of bars over which the web passes, guide collars carried by said bars for maintaining the 20 transverse alinement of the web, and brake fingers bearing upon said web at its contact with said bars.

4. In a salesbook making and printing machine, the combination with a plurality of rotative printing elements, of feeding 25 means for conducting and supporting an alternately tight and loose web to said printing elements, said printing elements acting upon said web during a portion of their rotation only, and during the time that they 30 act upon said web, serving to accelerate the same, bars disposed both in advance and in rear of said printing elements, and brake fingers co-acting with said bars to prevent 35 overthrow of the web when said web is accelerated.

5. In a salesbook making and printing machine, the combination with a plurality of rotative printing elements, of feeding means for conducting and supporting an

alternately tight and loose web to said printing elements, said printing elements acting upon said web during a portion of their rotation only and during the time that they act upon said web serving to accelerate the same, bars disposed both in advance and in rear of said printing elements, brake fingers co-acting with said bars to prevent overthrow of the web when said web is accelerated, and guide collars carried by said bars to maintain the transverse alinement 50 of the web.

6. In a salesbook making and printing machine, the combination with a plurality of rotative printing elements, of feeding means for conducting and supporting an alternately tight and loose web to said printing elements, said printing elements acting upon said web during a portion of their rotation only and during the time that they act upon said web, serving to accelerate the same, bars disposed both in advance and in rear of said printing elements, brake fingers co-acting with said bars to prevent overthrow of the web when said web is accelerated, guide collars carried by said bars to maintain the transverse alinement of the web, feed rollers over which the web passes, a rotative member acting in conjunction therewith, and means for driving said member in either direction, whereby it may be caused to accelerate or retard the web, at will.

In testimony whereof I affix my signature in presence of two witnesses.
